QUICK SHIFT ROOTER

Dean Fletcher, Wildomar, Calif.

Application January 9, 1940, Serial No. 313,110

6 Claims. (Cl. 262—8)

There is a known machine of the push-scraper type, known as a "bulldozer," embodying a mouldboard disposed transversely of the line of advance, the bulldozer forming the forward part of a motor-propelled vehicle, or being assembled therewith.

In tearing up hard ground, oiled roads and the like, a mouldboard is not sufficient. This invention aims to supply a novel form of rooter or digger, extended below the mouldboard of a bulldozer, road-maintainer or grader, the rooter or digger being of novel form, and novel means being supplied for assembling it with the mouldboard.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows, in front elevation, a device constructed in accordance with the invention, assembled with a mouldboard of a machine of the general sort hereinbefore alluded to;

Fig. 2 is a vertical section on the line 2—2 of Fig. 1;

Fig. 3 is a vertical section showing a modification;

Fig. 4 is a vertical section showing another modification;

Fig. 5 is a vertical section showing a further modification;

Fig. 6 is a section on the line 6—6 of Fig. 5;

Fig. 7 is a vertical section showing still another modification;

Fig. 8 is a vertical section illustrating another modification;

Fig. 9 is a horizontal sectional view illustrating a further modification;

Fig. 10 is a sectional view showing another modification.

Referring first to Figs. 1 and 2, the numeral 1 marks the framework of a push-scraper, or bulldozer or analogous implement, to which is secured a rearwardly concaved mouldboard 2, which is provided at its upper edge with a rearwardly-extended flange 3.

The device forming the subject matter of this

application is made of metal throughout. It embodies parallel uprights 4, which are rigid bars, rearwardly curved, to conform to the forward concavity of the mouldboard 2. The uprights 4 are connected by an upper cross piece 5 and a lower cross piece 6, disposed in parallel relation and at right angles to the uprights 4. The ends of the cross pieces 5 and 6 may be connected to the uprights 4 by welding or otherwise. The lower cross piece 6 is located at the lower edge of the mouldboard 2, and the upper cross piece 5 is located nearer the flange 3 of the mouldboard 2 than to the lower edge of the mouldboard. The uprights 4 are provided at their upper ends with backwardly extended hooks 7 which rest on the flange 3, the bills of the hooks 7 extending under the flange 3, and the bills being beveled, as indicated at 8, to facilitate the assembly of the device with the mouldboard 2 and its flange 3.

The uprights 4 extend any desired distance below the lower edge of the mouldboard 2, and they terminate in reduced lugs 9, whereon detachable and renewable soil-engaging points 10 are mounted.

As to general operation, when the vehicle is advanced, the lower parts of the uprights 4 and the points 10, extending below the lower edge of the mouldboard 2, will function to rip up plowed ground, a roadway or the like.

The rooter is assembled with the mouldboard 2 by lifting up the device, engaging the hook 7 with the flange 3 and permitting the device to swing downward to place against the forward surface of the mouldboard 2, as shown in Fig. 2.

Specifically stated, the rooter is of ladder-like form, and comprises horizontally spaced uprights 4, and vertically spaced, substantially horizontal connectors joining the uprights, the connectors being of such width and thickness that they can be grasped in the human hand and serve as grips during the assembly of the rooter with a mouldboard and during the detachment of the rooter therefrom, two of the connectors being located close enough together, and being so disposed with respect to opposite ends of the rooter, as to distribute the weight of the rooter with substantial equality when it is handled by means of the connectors.

Recalling the severe duty that the rooter is required to perform, it is needless to point out that it must be of considerable weight and not easy to handle unless constructed specifically with that end in view. In the placing of the rooter on the mouldboard 2, the cross pieces 5 and 6 constitute handles whereby the article can

be lifted and manipulated conveniently. The parts 5 and 6 form connections of great strength, holding the uprights 4 in parallel relation. The net result is a structure of adequate strength and necessarily somewhat heavy, but capable, nevertheless, of being handled advantageously.

In Fig. 3, parts hereinbefore described have been designated by numerals already used, with the suffix "a." The flange 3a of the mouldboard 2a is thicker than the corresponding flange 3 of Fig. 2. Each upright 4a comprises a lower part 11 and an upper part 12, connected by a hinge 14, the axis of which is parallel to the mouldboard 2a, horizontally considered. The upper member 12 of each upright 4a has a backwardly extended, rectangularly disposed arm 15, fitting on top of the flange 3a but not hooked underneath it. Securing elements 16, such as bolts, pass through the upper member 12 of each upright 4a, and through the flange 3a. Owing to the provision of the hinge 14, the lower part 11 of the upright 4a will find abutment against the mouldboard 2a. Furthermore, because the hinge 14 is provided, the vehicle can be set aback readily, the lower portion 11 of the rooter swinging forwardly and dragging over the surface of the ground or roadway, an observation which will be understood readily when Fig. 3 is noted.

In Fig. 4, parts hereinbefore described have been designated by numerals already used, with the suffix "b." The uprights 4b of the rooter are of one-piece construction, as in Fig. 2. The arm 15b has a bill 17 that extends down behind the flange 3b, the bill being beveled on its inner edge, as shown at 8b, for easy assembly.

Each upright 4b is provided with a rearwardly extended lug 18 that passes through a hole 19 in the mouldboard 2b, the lug being provided with a vertical opening 20, into which may be inserted a wedge key 21, engaging the rear surface of the mouldboard 2b, to aid in holding the rooter in place.

In Figs. 5 and 6, parts hereinbefore described have been designated by numerals already used, with the suffix "c." Forwardly-presented ears 22 are secured to the mouldboard 2c, by welding or otherwise. The ears 22 have circular openings 23. The opening 23 in one ear is provided with a reduced, rearwardly prolonged extension 24. The uprights 4c of the rooter have circular openings 25. The opening 25 in one upright 4c is supplied with a reduced, upwardly prolonged extension 26.

The rooter is disposed in a substantially-horizontal, forwardly-extended position. This lines up the extension 26 with the extension 24. The numeral 27 marks a connector or pin, having a radial arm or handle 28. The pin 27 is thrust through the aligned openings 25 of the uprights 4c, and through the corresponding openings 23 of the ears or supports 22, the pin 27 having an outstanding radial projection 29 that passes inwardly through the aligned extensions 24 and 26.

The handle 28 is swung down against the mouldboard 2c and the projection 29 is so disposed that the pin 27 cannot escape while the slot extensions 24 and 26 are still in line. The rooter then is swung down to place against the mouldboard 2. This disposes the extensions 24 and 26 out of line, as shown in Fig. 5. The projection 29 is inside one upright 4c, as shown in Fig. 6, the head 28 of the pin engages the corresponding ear 22, and the pin 27 cannot escape lengthwise.

In Fig. 7, parts hereinbefore described have

been designated by numerals already used, with the suffix "d." Ears 22d are secured to the top of the mouldboard 2d and are connected by a pin 31. The arm 15d of each upright 4d is provided in its top with a notch 32 adapted to receive the pin 31.

In Fig. 8, parts hereinbefore described have been designated by numerals already used, with the suffix "e." A U-shaped bracket 33 is secured to the forward surface of the mouldboard 2e, by any desired number of bolts 36, and has forwardly presented ears 34, connected by a pin 35. The upper part of each upright 4e has a horizontal notch 37, adapted to receive the pin 35.

In Fig. 9, parts hereinbefore described have been designated by numerals already used, with the suffix "f." This form of the invention is very much like the one depicted in Fig. 8, aside from the fact that the notches 37 of Fig. 8 are replaced by openings 37f, through which the pin 35f passes.

In Fig. 10, parts hereinbefore described have been designated by numerals already used, with the suffix "g." The projection or lug 29 of Fig. 6, and associated parts, are dispensed with, the pin 27g being held in place by a cotter pin 30.

In any of its forms, the device will be found thoroughly advantageous for the ends in view and hereinbefore set forth.

In all forms of the invention except in Fig. 4, there is embodied a mouldboard, a rooter co-operating with the forward surface of the mouldboard and comprising a soil-engaging portion 35 extended below the mouldboard, and means for assembling the rooter with the mouldboard to permit the soil-engaging portion of the rooter to swing forwardly when the mouldboard is moved backwardly.

Having thus described the invention, what is claimed is:

1. A rooter for attachment to the mouldboard of a scraper, the rooter being of ladder-like form and comprising horizontally spaced uprights and vertically spaced, substantially horizontal connectors joining the uprights, the connectors being of such width and thickness that they can be grasped in the human hand and serve as grips during the assembly of the rooter with a mouldboard and during the detachment of the rooter therefrom, two of the connectors being located close enough together, and being so disposed with respect to opposite ends of the rooter, as to distribute the weight of the rooter with substantial equality when it is handled by means of the connectors, and means assembled with the upper portions of the uprights for positioning the rooter on a mouldboard.

2. A rooter for attachment to the mouldboard of a scraper, constructed as set forth in claim 1, and wherein the last-specified means comprises a backwardly extended arm on the upper portion of each upright, and a securing device passing through each upright and engageable with a mouldboard in the close vicinity of the arm.

3. A rooter for attachment to the mouldboard of a scraper, constructed as set forth in claim 1, and wherein each upright comprises hingedly connected upper and lower parts, permitting the lower parts to swing forwardly when the scraper is set aback.

4. In a device of the class described, a mouldboard carrying projecting ears, a pin mounted in the ears, and a rooter resting against the

forward surface of the mouldboard and extended between the ears, the rooter having an opening receiving the pin, the rooter being of ladder-like form and comprising horizontally spaced uprights and vertically spaced, substantially horizontal connectors joining the uprights, the connectors being of such width and thickness that they can be grasped in the human hand and serve as grips during the assembly of the rooter with a mouldboard and during the detachment of the rooter therefrom, two of the connectors being located close enough together, and being so disposed with respect to opposite ends of the rooter, as to distribute the weight of the rooter with substantial equality when it is handled by means of the connectors.

5. In a device of the class described, a mouldboard carrying projecting ears, a pin mounted in the ears and a rooter resting against the forward surface of the mouldboard and extended between the ears, the rooter having an upwardly opening notch receiving the pin, the rooter being of ladder-like form and comprising horizontally

spaced uprights and vertically spaced, substantially horizontal connectors joining the uprights, the connectors being of such width and thickness that they can be grasped in the human hand and serve as grips during the assembly of the rooter with a mouldboard and during the detachment of the rooter therefrom, two of the connectors being located close enough together, and being so disposed with respect to opposite ends of the rooter, as to distribute the weight of the rooter with substantial equality when it is handled by means of the connectors.

6. A rooter constructed as set forth in claim 1, and wherein the last-specified means is a backwardly extended hook at the upper end of each upright, for engagement with the backwardly extended flange of a mouldboard, the space within the bill of the hook widening as it extends forwardly, whereby the rooter can swing forwardly with respect to a mouldboard when the mouldboard moves backwardly.

DEAN FLETCHER.
